SAFETY RAZOR

Theodore G. McGirr and Theodore M. Husch,
Brooklyn, N. Y.

Application October 16, 1933, Serial No. 693,850

5 Claims. (Cl. 30—12)

This invention relates to that class of safety razors formed into a package similar to a pocket package of cardboard matches, and the invention has for its object to provide a razor, of the 5 class referred to, which will avoid certain manufacturing difficulties incident to razors, heretofore known, of said class. To this end our improved razor consists, aside from certain fastening devices, of only four parts, to wit: a paper 10 or card-board cover, a guard plate, a blade and a comb guard for the blade, all constructed and arranged as hereinafter set forth.

In the accompanying drawing Fig. 1 is a perspective back view of the improved razor in folded 15 or pocket shape. Fig. 2 is a perspective view of the same with the parts in position for use. Fig. 3 is a front view with the parts disposed as in Fig. 2. Fig. 4 is an edge view looking from the right of Figs. 2 and 3. Fig. 5 is a section on line 20 5—5, Fig. 3. Fig. 6 is a back view with the parts disposed as in Fig. 1.

Referring to the drawing, 12 denotes a flexible 25 foldable cover preferably of thin cardboard, said cover comprising an infolded flap 12^a and a tab 12^b adapted to be tucked beneath said flap when the parts of the razor are in folded or pocket 30 position. The flap 12^b is suitably secured to the body of the cover, at its outer side parts, as by clinched staples 13. This fastened down flap affords a pocket in which said tab fits to hold the 35 doubled parts of the cover together flatwise to afford a handle.

Attached to the cover 12 and to each other, 40 preferably by eyelet rivets 14, are a guard comb 15, a blade 16 and a guard plate 17 superposed on said blade, said guard plate having an in-turned lip 17^a back of the blade 16.

From the foregoing it will be understood that 45 our improved razor consists of few simple parts which may be readily manufactured and which may be easily adjusted from folded or pocket position to operative or usable position. The guard comb 15 consists of a single piece which may be readily stamped out of sheet metal, and 50 then be bent into operative shape as shown in the drawing. The cover may have any suitable advertising material printed thereon, as is common with packages of card-board matches. The cover 12 is suitably creased transversely so that 55 it will naturally fold at predetermined places, either to closed or operative positions. When what appears as the upper flap of the cover in Fig. 1 is folded backward flatwise toward the other flap to the position shown in Figs. 4 and 5, to adjust the parts for shaving, these two flaps, supplementing and stiffening each other, 60 serve as a handle to be grasped by the thumb and fingers of the user, as will be understood.

It may be noted that the one-piece doubled 65 comb guard, with its inner and outer parts sepa-

rated, affords a considerable space, back of the comb or toothed part of said guard, for the reception of lather which may accumulate in shaving.

The lather will be received in the pocket afforded by the upturned parts of the doubled comb guard, as will be understood by reference to Figs. 4 and 5.

Having thus described our invention we claim and desire to secure by Letters Patent:

1. A safety razor comprising a foldable flexible cover of thin cardboard, suitably creased transversely so that it will fold at predetermined places, and having an infolded flap attached at its outer side parts to the body of said cover, thus affording 15 a pocket, said cover having also a tab adapted to be inserted in said pocket, a one-piece doubled comb-guard, a blade, a metal guard plate overlying said blade and said comb guard, and means for securing said parts together, said blade being 20 interposed between said comb guard and said guard plate.

2. A safety razor comprising a foldable flexible cover of thin cardboard suitably creased transversely so that it will fold at predetermined 25 places, a doubled one-piece comb guard member having separated inner and outer parts affording a lather-receiving pocket back of its front, a blade, a metal guard plate overlying said blade and said comb guard, and means for securing 30 said parts together, said blade being interposed between said comb guard and said guard plate.

3. A safety razor comprising a flexible cover of thin cardboard suitably creased transversely so that it will fold at predetermined places, a doubled 35 one-piece comb guard affording a pocket for the reception of lather, a blade, a metal guard plate overlying said blade and comb guard and having an inturned lip back of said blade, and means for securing said parts together, said blade being 40 interposed between said comb guard and said guard plate.

4. A safety razor according to claim 3 in which the flexible cover is adapted to be doubled on 45 itself flatwise to form a handle, said cover having a tab and also a pocket in which said tab fits to hold the doubled parts together in serving as a handle.

5. A safety razor comprising a foldable cover 50 of thin cardboard suitably creased transversely so that it will fold at predetermined places, a one-piece doubled comb guard, a blade, a metal guard plate located outside of said blade, and means for securing said parts together, said blade 55 being interposed between said comb guard and said guard plate.
